UNITED STATES PATENT OFFICE.

JAMES W. DENNIS, OF CINCINNATI, OHIO, ASSIGNOR OF ONE-HALF TO
WILLIAM HAMILTON, OF SAME PLACE.

GUN-WAD.

SPECIFICATION forming part of Letters Patent No. 295,235, dated March 18, 1884.

Application filed November 5, 1883. (No model.)

To all whom it may concern:

Be it known that I, JAMES W. DENNIS, a citizen of the United States, residing at Cincinnati, Ohio, have invented new and useful Improvements in Gun-Wads, of which the following is a specification.

My invention has reference to gun-wads, such as are used in cartridge-shells. As heretofore used, such wads, usually made of felt or paper material, are apt to become displaced by the shock and jar of firing adjacent barrels in double-barreled weapons, and to prevent such displacement concave star-shaped pieces of thin sheet metal have been used, which, when placed upon the wad and flattened, were intended by their enlargement to project the peripheral points into the surrounding wall of the cartridge and form a holder for the wad. The force, however, driving the points outward, being applied at or near the center of the concave circle or star, is transmitted thence radially so far as often to cause the "buckling" of the metal without forcing the points into the cartridge. Moreover, the holder having no connection with the wad, it derives no strength therefrom. For these and other reasons this device has proven, in many cases, inefficient, besides being from its form troublesome to pack and transport, and also to place in position for use.

My present invention is intended to remedy these difficulties; and it consists, primarily, in a novel form and construction of a sheet-metal wad-holder.

It further consists in a combined wad and wad-holder; and it further consists in novel constructions of wads, introducing other functions rendered possible by such general combination, all as hereinafter more fully described.

My invention is illustrated in the accompanying drawings, in which Figure 1 is a plan view and corresponding cross-section of my improved wad-holder detached. Fig. 2 is a partial vertical cross-section of a loaded cartridge, showing the outer wad and holder in position, ready for the flattening process; Fig. 3, a similar cross-section, showing the wad-holder flattened and expanded; Fig. 4, an under plan view and corresponding cross-section of an annular wad combined with a wad-holder designed to concentrate the load of shot in firing; and Fig. 5, a similar under plan and cross-section of a

"cross wad" combined with a wad-holder designed to disperse or "scatter" the shot in firing.

Referring to the drawings, the wad-holder (designated by the letter A) is a disk of thin sheet metal formed with an annular groove, *a*, near its margin. Its extreme edge may be serrated, if desired; but ordinarily this is not necessary, as the expanding force developed in flattening the annular groove is applied so near the margin as to expand the entire margin uniformly into the surrounding wall of the cartridge. To facilitate this expansion, a number of radial cuts, *b*, are made in the metal disk from its outer margin into the annular groove—usually four or eight, at equal distances, are sufficient. When used, it is further desirable that the disk A should be firmly united with the wad B, and this may be accomplished by making angular cuts, as at *c*, through the metal, and turning down the points *c'*, which, in the flattening process, sink into the substance of the wad B and secure the disk thereto; or the same result may be accomplished by perforating the metal disk, as at *d*, and securing the disk to the wad by a tack, *d'*, passing through such perforation, of which there may be one or more.

Although the disk A may be used separately, it is far more convenient to permanently unite the same with the wad, as an article of manufacture ready for immediate use, requiring only the expansion of the disk by ramming and flattening the groove after the wad is in position. Such construction is rendered possible by the form of the disk and the provision for union with the wad, and constitutes an important advantage over the ordinary concave disk. This combination, moreover, renders it possible to construct the combined wad and holder in the forms shown in Figs. 4 and 5. In the first of these the wad B is perforated, preferably, with a central conical perforation, as shown, the metal disk thus serving as an upper wall to the perforation; and being secured to the wad by tacks *d'*, or otherwise, around the perforation, constitutes a strengthening-brace throughout. In the ramming process, the shot is forced upward, filling the perforation, and when the load is discharged the effect is to concentrate the fire. In the construction shown in Fig. 5, the reverse effect is attained

by perforating the wad at the margin, thereby separating the shot and increasing the quantity at the margin and diminishing it centrally, the disk, as before, serving as a strengthening support and as an outer wall for holding the shot.

The form and arrangement of the perforations may be varied, as will be obvious, without departing from the spirit of my invention.

10 The combined wad thus described may be used with advantage in the ordinary loading of gun-barrels, the expansion of the metal disk against the barrel causing the wad to better retain its place, and the metal thus forming a 15 scraper in its exit through the barrel, tending to keep the barrel clean.

Having described my invention, I claim and desire to secure by Letters Patent—

1. A holder for gun-wads, consisting of a flat sheet-metal disk having an annular groove at 20 or near the margin, and adapted to be secured

to the wad in using, and expanded by flattening, substantially as set forth.

2. A combined gun-wad and holder, consisting of a wad of paper or soft material having 25 united therewith a flat metal disk provided with an annular groove adapted to be expanded by the ramming process against or into the wall of the cartridge or barrel, substantially as set forth.

3. The improved gun-wad, consisting of a paper or felt wad perforated centrally or marginally, and provided with a sheet-metal disk 30 united therewith at one of its outer surfaces, substantially as set forth.

In testimony whereof I have hereunto set my hand in the presence of two subscribing witnesses.

JAMES W. DENNIS.
